UNITED STATES PATENT OFFICE.

ALEXANDER LAUBSCHER, OF BRIDGEPORT, CONNECTICUT, ASSIGNOR TO WHEELER & WILSON MANUFACTURING COMPANY, OF BRIDGEPORT, CONNECTICUT, A CORPORATION OF CONNECTICUT.

MACHINE FOR SEWING SWEAT-BANDS IN HATS.

No. 822,135.

Specification of Letters Patent.

Patented May 29, 1906.

Application filed June 24, 1905. Serial No. 266,793.

To all whom it may concern:

Be it known that I, ALEXANDER LAUBSCHER, a citizen of the United States, residing at Bridgeport, in the county of Fairfield and State of Connecticut, have invented a certain new and useful Improvement in Machines for Sewing Sweat-Bands in Hats, of which the following is a full, clear, and exact description.

10 This invention relates more particularly to machines for sewing sweat-bands into stiff, felt, or other hats having a roll brim, although it may be used on other sewing-machines, if desired.

15 The object of the invention is to provide more convenient means for placing the hat in and out of sewing position.

In the present invention is provided means which permits the operator to turn the front 20 portion or head of the overhanging arm and its attached parts out of a vertical line or to one side of its operative position and without disconnecting any of the operative parts, the lowering and raising of the presser-bar acting 25 to lock and unlock the head relatively to the fixed portion of the overhanging arm, all as will now be described and finally pointed out particularly in the claims.

30 In the accompanying drawings, illustrating the invention, in the several figures of which like parts are similarly designated, Figure 1 is a front side elevation of a hat-sweat sewing-machine, the work-support in section and the sewing-machine base and 35 overhanging arm partly in section. Fig. 2 is a front end elevation, the face-plate being removed to expose the parts located in the front end of the overhanging arm. Fig. 3 is a front end view of the overhanging arm 40 shown in Fig. 2 with head portion turned to one side of its vertical or operative position. Fig. 4 is a rear side elevation of the front portion of the overhanging arm. Fig. 5 is a perspective view of the feed-dog-actuating mechanism. Fig. 6 is a front elevation similar to Fig. 3, but with the needle-bar and presser-bar removed.

45 1 is a supplemental base, upon which the sewing-machine base 2 is secured by a suitable hinge-joint 3, latch 4, and catch 5.

50 6 is the work-support, 7 the overhanging arm, and 8 the arm-standard, said base 2,

work-support 6, arm 7, and standard 8 comprising a single casting.

9 is the lower main shaft; 10, the band-wheel; 11, the shaft-flange; 12, the shaft-flange stud; 13, the loop-taker; 14, the loop-taker driver; 15, the loop-taker-driver shaft; 16, the loop-taker-driver shaft-crank, and 17 the shaft-crank stud.

18 is the variable-motion link, the opposite ends of which are mounted upon studs 12 and 17, respectively, thus operatively connecting the lower main shaft 9 with the loop-taker-driver shaft 15.

19 is the take-up cam, secured to the lower main shaft 9; 20, the take-up rocker; 21, the take-up-rocker stud, and 22 the take-up lever.

23 is the knurled head of a screw 24, tapped in an arm 25 of a bell-crank lever 26, which is fulcrumed in a bearing 27 in the base 2. To the other arm 28 of said bell-crank lever is pivotally secured a link 29, which is pivotally attached to a forked lever 30. This lever engages an eccentric 31, carried by the lower main shaft 9, and the opposite end 32 of lever 30 is pivotally attached to a crank 33, secured to a feed rock-shaft 34, mounted in suitable bearings 35 and 36 on the base and 30 work-support. The forward end of the feed rock-shaft is provided with a crank 37, to one end of which is secured a link 38, which is pivotally secured to a lug 39 on the feed-dog-carrying bar 40. To this bar 40 is adjustably secured by a screw 41 the feed-dog 42 for feeding the hat to the action of the needle 43. A second feed-dog 44 is adjustably secured by a screw 45 to an extended portion 46 of the feed-dog-carrying bar 40, said feed-dog 44 being located at the rear side of the loop-taker 13 and operated to advance the sweat-band synchronously with the feed of the hat. Vertical movements are imparted to the feed-dogs 42 and 44 by an eccentric 47 on shaft 9, 95 coacting with a forked lever 48, secured on a lift rock-shaft 49, mounted between pintle-bearings 50 and 51, tapped in bearings 52 and 53 in the base 2 and work-support 6.

On the lift rock-shaft 49 are two lugs 54 and 55, between which is secured by pintle-screws 56 and 57 the feed-dog-carrying bar 40, so that by the action of eccentric 47 vertical movements are given the feed-dog

through the connections pointed out, and by eccentric 31 through the connections pointed out feed movements are transmitted to the feed-dog.

5 58 is the throat-plate, secured by screws 59 to the work-support 6.

60 is the bobbin-case, mounted in the usual manner in the loop-taker 13 and held against accidental displacement by the latch 61.

10 The edge gages (shown in Fig. 1) are common to the Wheeler & Wilson hat-sweat sewing-machine, and the same is true of all the parts 1 to 61, inclusive, hereinbefore referred to, with the exception of the overhanging arm 7.

15 Referring to the improvements, 62 is a bushing adjustably secured by screw 63 in the front end of the overhanging arm 7 and provided with a flange 64, which enters a seat 65, formed in a swinging head 66, which head is thereby pivotally mounted upon said bushing 62. By the lengthwise adjustment of the bushing 62 the face 67 of the overhanging arm and the face 68 of the swinging head are held in adjustment relatively to each other, so that the head 66 may be swung upon the bushing 62 without lost motion between the faces 67 and 68.

20 69 is a hand rock-shaft mounted at its forward end in the bushing 62, its opposite end mounted in a bearing 70 in the overhanging arm. The forward end of said rock-shaft is provided with a lever 71, through one end of which passes loosely a screw 72, tapped in the 25 wall 73 of the swinging head 66, and at its opposite end shaft 69 is provided with a hand-lever 74, so that the operator may turn the head 66 out of operative position, as in Fig. 3, and return it to its operative position, as in 30 Figs. 1, 2, and 4.

35 75 is a needle-bar mounted in bearings 76 and 77, suitably secured in the swinging head 66, the lower end of said bar being provided with a needle-bracket 78, in which is secured 40 the needle 43.

45 79 is the needle-bar rock-shaft, mounted in suitable bearings in the overhanging arm 7 and provided with a lever 80, which is pivotally attached to a link 81, the opposite end 50 of said link being pivotally mounted upon a stud 82, having a collar 83, secured by screw 84 to the needle-bar 75, thus operatively connecting the needle-bar with the rock-shaft 79. To the rear end of the rock-shaft 79 is secured a crank 85, connected by an eccentric-rod 86 with an eccentric 87, fast on the lower main shaft 9, thus operatively connecting the 55 lower main shaft 9 with the needle-bar 75.

88 is the presser-bar, mounted in the bearings 89 and 90, the former being adjustable, so as to compress more or less the spring 91, encircling the presser-bar, so as to adjustably control the amount of pressure given the presser-foot 92 upon the material.

60 93 is the presser-lifter collar, secured by

screw 94 to the presser-bar and provided with two arms 95 and 96, the former acted upon by the presser-lifter 97 to raise the presser-foot above the material, the free end of the second arm 96 acting upon a pin 98, secured in a bell-crank lever 99, the short arm of which bell-crank lever is pivotally secured by screw 100 to the swinging head 66, its longer arm entering a notch 101, formed in a bolt 102, which latter is mounted in a pocket 70 75 103, formed in the inner wall of the rear side of the swinging head 66, which bolt acts to lock the swinging head to the face 67 of the overhanging arm by the end of the bolt passing into a suitable hole 104. The opposite 80 end of the bolt is acted upon by a spring 105, secured by screw 106 to hold said bolt in locking position.

107 is a collar secured by screw 108 on the presser-bar and provided with an arm 109, which extends upward and at its free end 110 is beveled to coact with the plunger 111, which plunger acts against the tension-disk 112 of the tension mechanism, so that when the presser-bar is lifted the beveled free end 90 110 of the arm 109 will force the plunger 111 against the tension-disk 112 in opposition to the resiliency of the tension-spring 113, thus releasing the tension from the needle-thread. This tension and tension-releasing mechanism is substantially the same as is common to Wheeler & Wilson sewing-machines generally. 95

Referring more particularly to Fig. 4, 114 110 114 is a bracket secured by screws 115 to the swinging head 66, and 116 is an adjustable stop secured by screws 117 to the overhanging arm 7. This stop has two lugs 118 and 119, the former acting to limit the swinging movement of the head 66 when moved into inoperative position and the latter acting to 105 register the head in its operative position, so that the bolt 102 will enter the hole 104 and lock the swinging head to the face 67 of the overhanging arm 7.

120 is a bracket constructed with a pinch-joint and secured by a screw 121 to the presser-bar 88, the free end of the bracket being forked to embrace the bearing 76 to prevent axial movement of said presser-bar.

The operation is as follows: Supposing the 115 work to be of such nature that an excessive clearance is desirable between the throat-plate 54 and cloth-presser 92—as, for instance, in the placing and displacing of a hat having a heavy roll stiff brim—the operator 120 by lifting the presser-bar causes the arm 96 to act upon the pin 98, secured in the bell-crank lever 99, thus rocking said lever on its pivot-screw 100 and through its connection with the bolt 102 causing said bolt to be 125 withdrawn from the hole 104, leaving the swinging head 66 free to be swung out of operative position on the bushing 62 by the manipulation of the hand-lever 74 or by the direct action of the hand upon the swinging 130

head. The head is returned in like manner to its operative position, the lowering of the presser-bar permitting the bolt 102 to again lock said head in its operative position.

- 5 By referring to Fig. 3 it will be seen that the axis of the stud 82 when the head 66 is adjusted to its inoperative position is substantially in line with the axis of the hand rock-shaft 69, thus permitting the head to be 10 swung in opposite directions without materially changing the position of the needle-bar, thus holding the needle-point guarded by the cloth-presser against injury.

What I claim is—

- 15 1. In a sewing-machine, an overhanging arm provided with a swinging head, a needle-bar-actuating shaft mounted in said arm, a needle-bar and a presser-bar mounted in said head, and connections between said needle-bar-actuating shaft and needle-bar, in combination with a locking device operatively connected with the presser-bar for securing said head against accidental movement when adjusted to sewing position.
- 25 2. In a sewing-machine, a work-support, an overhanging arm, a head pivoted to said arm, a needle-bar and a presser-bar mounted in said head, a horizontal rock-shaft mounted in the overhanging arm and provided with 30 a hand-lever at one end and connected with said pivoted head at its other end and adapted to rock said head on its pivot to throw the needle-bar and presser-bar to one side of the work-support, an automatic locking device 35 for locking the head to the arm in its sewing

position, and means actuated by the presser-bar to unlock the locking mechanism to permit the head to be swung out of sewing position.

3. In a sewing-machine, the combination 40 of a main shaft, a needle-carrying bar, a presser-bar, a stationary overhanging arm, a needle-bar-carrying head adjustably secured to said arm, a needle-actuating shaft and connections between said needle-bar and its 45 actuating-shaft, a loop-taker connected with the main shaft and connections between said main shaft and needle-actuating shaft, a locking device carried by said adjustably-secured head and connected with the presser-bar, and stops for limiting the movements of 50 said swinging head in opposite directions.

4. In a sewing-machine, a work-support, an overhanging arm, a head pivoted to said arm, a needle-bar and a presser-bar mounted 55 in said head, means to rock said head on its pivot to throw the needle-bar and presser-bar to one side of the work-support, an automatic locking device for locking the head to the arm in its sewing position, and means actuated by the presser-bar to unlock the locking mechanism to permit the head to be 60 swung out of sewing position.

In testimony whereof I have hereunto set my hand this 20th day of June, A. D. 1905.

ALEXANDER LAUBSCHER.
